SMALLWARE LOOM

Garford Lilley, John Raymond Lilley, and Eric
Ronald Lilley, Derby, EnglandApplication July 30, 1941, Serial No. 404,668
In Great Britain November 2, 1940

8 Claims. (Cl. 139—199)

This invention relates to small ware looms and particularly to improvements in the shuttle or weft carrying devices thereof.

The main object of the invention is to increase the yarn carrying capacity of the shuttle but other objects are to ensure an even tension on the yarn from a full shuttle until the yarn is exhausted and to enable the shuttle to be removed from the loom for replenishment whereby an empty shuttle can immediately be replaced by a full shuttle already threaded and the empty shuttle afterwards replenished for subsequent insertion in the loom.

In the usual shuttle of a small ware loom the yarn is wound on to a bobbin or tube which is mounted on a quill or spindle parallel with the direction of movement of the shuttle and this quill or spindle is necessarily situated in the part of the shuttle which projects forwardly from the batten. The available space for the bobbin is thus restricted and the maximum diameter of a full bobbin is limited to such available space.

According to the present invention the yarn package is mounted on a spindle arranged in the shuttle at right angles to the direction of movement of the latter and instead of the shuttle being in direct engagement with the shuttle track on the batten it is carried by a holder from which it can be detached for replenishment of the yarn and which also allows it to project to the rear of the shuttle track into the space between the latter and the reed. In this way a yarn package containing a much greater length of yarn than the usual bobbin can be accommodated in the shuttle with a corresponding increase in the length of time which the shuttle will run without replenishment.

A further feature of the invention is that the shuttle is constructed in two parts, a rear part which carries the spindle to receive the yarn package and a front part in which the eye for the passage of the yarn is located and which also carries the means for applying the required drag or tension to the yarn, the two parts being locked together and to the shuttle holder when inserted into the latter.

The invention is illustrated in and will be described with reference to the accompanying drawing, in which—

Fig. 1 is a side view of the shuttle and shuttle holder.

Fig. 2 is an end view thereof looking in the direction of arrow 2, Fig. 1.

Fig. 3 is an end view thereof looking in the direction of arrow 3, Fig. 1.

Fig. 4 is a plan thereof.

Fig. 5 is a longitudinal section on line 5—5 Fig. 4.

Fig. 6 is a horizontal section on line 6—6 Fig. 1.

Fig. 7 is a transverse section on line 7—7 Fig. 4.

Fig. 8 is a side view of the front part of the shuttle.

Fig. 9 is a side view of the rear part of the shuttle.

5 Fig. 10 is a plan of the rear part of the shuttle.

Fig. 11 is a section on line 11—11 Fig. 10.

Fig. 12 is a side view of the shuttle holder.

Fig. 13 is a front view of the shuttle holder.

The shuttle is constructed in two parts, a rear 10 part A which carries the spindle a on which the yarn package C is mounted and which projects rearwardly from the shuttle track in the batten into the space between the latter and the reed and a front part B which projects forwardly 15 from the said track.

The rear part A, which projects to the rear of the shuttle holder consists of a longitudinal member a¹ and two forwardly projecting side members a², the spindle a being secured to the 20 longitudinal member and projecting forwardly therefrom midway between and parallel with the side members a².

The front part B is of magnet or horse shoe shape with the side members b thereof parallel 25 with one another. The rear end b¹ of each side member b is preferably rectangular in cross section and adapted to fit into the corresponding side members a² of the rear part A when the two parts are assembled together. Each side member a² of the rear part A is formed of two resilient strips a³ between which the end b¹ of the corresponding side b of the front part B is inserted 30 and which when the shuttle is inserted in the shuttle holder D will be pressed onto the side b of the front part and projections a⁴ at the front ends of the strips a³ caused to engage in corresponding grooves or recesses b⁴ in the top and bottom surfaces of the side member b of the front part B thereby locking the parts A and B 35 together.

The shuttle eye b² is formed centrally in the curved front end b³ of the front part B, a drag or tension device being arranged between the nose of the yarn package C and the eye b². The tension device consists of a pair of small toothed or fluted rollers E¹ and E², the roller E¹ being mounted on a fixed pin e¹ and the other roller E² on a pin e² carried at the end of a bent steel or other resilient arm E secured in a groove b⁵ 40 in one of the side members b at some distance from the front of the shuttle so that the roller E² carried thereby can move to and from the roller E¹ on the fixed pin e¹. The arm E is acted upon by a light spring E³ to apply the necessary tension to the yarn y as it passes between the rollers E¹ and E². The arm E³ also carries a thread guide e³ which serves to guide the yarn y into the nip of the rollers E¹ and E².

The shuttle holder D is of rectangular shape 45 with a central longitudinal slot d through which

the rear end of the shuttle is inserted after the two parts thereof have been assembled together. The length of the slot d is the same as the width of the shuttle and its depth at the ends corresponds to the depth of the shuttle. The middle parts d^1 of the top and bottom of the slot are however curved to permit of yarn packages C of greater diameter than the depth of the shuttle being carried by the spindle a.

A catch F controlled by a spring f is pivotally mounted on a pin f^1 located in the groove b^3 in one of the side members b of the front part B and engages behind the holder D when the shuttle is inserted into the latter thus locking the shuttle in the holder and since as before stated the two parts A and B of the shuttle are locked together by the pressure of the holder on the resilient side members a^2 of the rear part A, the two parts of the shuttle and the holder are securely held together.

To remove the two parts A and B of the shuttle from the holder D for replenishing the yarn package it is only necessary to depress the spring catch F when the shuttle can be pulled out from the holder. The pressure holding the side members a^2 of the rear part on the ends b^1 of the side members b of the rear part is at the same time removed so that the two parts can be separated and a new yarn package placed on the spindle a. The two parts can then be reassembled together, the yarn threaded through the tension device and eye and the shuttle is ready for replacement in the shuttle holder when the next replenishment is required.

The top and bottom faces of the holder D may each be formed with a longitudinal groove d^2 and the shuttle tracks on the batten formed with corresponding ribs which enter the grooves d^2 thereby increasing the bearing surface of the holder.

Since the part A of the shuttle extends rearwardly of the holder D and therefore of the shuttle track in the batten of the loom and the spindle a on which the yarn package C is mounted is carried by the part A and projects through the holder it is evident that a yarn package of considerable size can be carried by the shuttle thereby permitting the use of yarn packages containing a much greater length of yarn than the bobbin which can be employed in the usual shuttle of a small ware loom with a corresponding increase in the length of time which the shuttle will run without replenishment.

A shuttle formed in accordance with the invention can be adapted for use with most types of small ware looms whether the shuttle is driven by vertical pegs or pins or by rack and pinion gearing and whether the shuttle moves horizontally or swivels in a curved path.

What we claim as our invention and desire to protect by Letters Patent is:

1. A weft carrying device for a small ware loom comprising in combination a rear part, a front part, a holder for the two parts which engages in the shuttle track of the loom, means for locking the two parts together and to the holder and a spindle carried by the rear part to support the yarn package which spindle projects both forwardly and rearwardly of the holder when the device is in the loom.

2. A weft carrying device for a small ware loom comprising in combination a rear part, a front part, a holder for the two parts which engages in the shuttle track of the loom, means for locking the two parts together and to the holder, a

spindle, carried by the rear part, which spindle supports the yarn package and which projects rearwardly of the shuttle track when the device is in the loom, a yarn eye for guiding the yarn carried by the front part and means also carried by the front part for applying tension to the yarn.

3. A weft carrying device for a small ware loom comprising in combination a rear part consisting of a longitudinal member and two forwardly projecting side members, a front part, a holder for the two parts which engages in the shuttle track of the loom, means for locking the two parts together and to the holder and a spindle which supports the yarn package secured to the longitudinal member of the rear part and projecting forwardly therefrom between and parallel with the side members.

4. A weft carrying device for a small ware loom comprising in combination a rear part consisting of a longitudinal member and two forwardly projecting side members, a front part, of horse shoe shape with the side members thereof parallel with one another, the rear end of each side member being rectangular in cross section and adapted to fit into the corresponding side member of the rear part when the two parts are assembled together, a holder for the two parts which engages in the shuttle track of the loom, means for locking the two parts together and to the holder and a spindle which supports the yarn package secured to the longitudinal member of the rear part and projecting forwardly therefrom between and parallel with the side members.

5. A weft carrying device for a small ware loom comprising in combination a rear part consisting of a longitudinal member and two forwardly projecting side members each formed of two resilient strips, a front member of horse shoe shape with the side members thereof parallel with one another, the rear end of each side member being rectangular in cross section and adapted to fit between the resilient strips forming the corresponding side member of the rear part, a holder for the two parts which when the two parts are inserted therein presses the aforesaid resilient strips on to the side members of the front part to lock the two parts together, means for locking the holder to the two parts, a spindle which supports the yarn package secured to the longitudinal member of the rear part and projecting forwardly therefrom between and parallel with the side members, a yarn eye in the front part and a tension device also carried by the front part for applying tension to the yarn.

6. A weft carrying device for a small ware loom comprising in combination a rear part consisting of a longitudinal member and two forwardly projecting side members each formed of two resilient strips, a front member of horse shoe shape with the side members thereof parallel with one another, the rear end of each side member being rectangular in cross section and adapted to fit between the resilient strips forming the corresponding side member of the rear part, a holder for the two parts which when the two parts are inserted therein presses the aforesaid resilient strips on to the side members of the front part to lock the two parts together, a spring controlled catch to lock the two parts to the holder, a spindle which supports the yarn package secured to the longitudinal member of the rear part and projecting forwardly therefrom between and parallel

with the side members, a yarn eye in the front part and a tension device also carried by the front part for applying tension to the yarn.

7. A weft carrying device for a small ware loom comprising in combination a rear part consisting of a longitudinal member and two forwardly projecting side members each formed of two resilient strips, a front member of horse shoe shape with the side members thereof parallel with one another, the rear end of each side member being rectangular in cross section and adapted to fit between the resilient strips forming the corresponding side member of the rear part, a holder for the two parts which when the two parts are inserted therein presses the aforesaid resilient strips on to the side members of the front part to lock the two parts together, a spring controlled catch to lock the two parts to the holder, a spindle which supports the yarn package secured to the longitudinal member of the rear part and projecting forwardly therefrom between and parallel with the side members, a yarn eye in the front part and a tension device also carried by the front part for applying tension to the yarn, said tension device consisting of two fluted rollers between which the yarn passes, one roller being mounted on a fixed pin and the other on a pin carried by a spring controlled flexible or resilient arm affixed to one side member of the front part.

8. A weft carrying device for a small ware loom comprising in combination a rear part consisting of a longitudinal member and two for-

wardly projecting side members each formed of two resilient strips, a front member of horse shoe shape with the side members thereof parallel with one another, the rear end of each side member being rectangular in cross section and adapted to fit between the resilient strips forming the corresponding side member of the rear part, a holder for the two parts which when the two parts are inserted therein presses the aforesaid resilient strips on to the side members of the front part to lock the two parts together, the said holder being of rectangular shape provided with a slot to receive the shuttle and allow the rear part to project beyond it, the central portion of the slot being enlarged to increase the space for the reception of the yarn package, a spring controller catch to lock the two parts to the holder, a spindle which supports the yarn package secured to the longitudinal member of the rear part and projecting forwardly therefrom between and parallel with the side members, a yarn eye in the front part and a tension device also carried by the front part for applying tension to the yarn, said tension device consisting of two fluted rollers between which the yarn passes, one roller being mounted on a fixed pin and the other on a pin carried by a spring controlled flexible or resilient arm affixed to one side member of the front part.
